US00D928834S

(12) **United States Design Patent** (10) **Patent No.:** **US D928,834 S**
(45) **Date of Patent:** **** Aug. 24, 2021**

(54) **DISPLAY SCREEN OR PORTION THEREOF WITH GRAPHICAL USER INTERFACE**

(71) Applicants: **SHANGHAI MAGIMA DIGITAL INFORMATION CO., LTD.**, Shanghai (CN); **BIBO NETWORK, LLC.**, San Jose, CA (US)

(72) Inventors: **Jen-Chung Chou**, Taipei (TW); **Qingyun Chen**, Shanghai (CN)

(**) Term: **15 Years**

(21) Appl. No.: **29/694,282**

(22) Filed: **Jun. 10, 2019**

(30) **Foreign Application Priority Data**

Dec. 25, 2018 (TW) 107307547

(51) **LOC (13) Cl.** **14-04**

(52) **U.S. Cl.**

Primary Examiner — Jack Reickel

(57) **CLAIM**

We claim the ornamental design for a display screen or portion thereof with graphical user interface, as shown and described.

DESCRIPTION

The sole FIGURE shows a display screen or portion thereof with graphical user interface, showing my new design. The long-short dashed broken line showing of a display screen or portion thereof and the broken line showing of a graphical user interface is included for the purpose of illustrating portions of the article and form no part of the claimed design.

1 Claim, 1 Drawing Sheet
